CARBIDE AGITATOR FOR ACETYLENE
GENERATORSMaurice P. De Motte, Indianapolis, Ind., assignor,
by mesne assignments, to Union Carbide and
Carbon Corporation, a corporation of New York

Application November 23, 1932, Serial No. 644,058

8 Claims. (Cl. 48—53.3)

The invention pertains to means for securing more uniform gas pressure in acetylene generators of the carbide to water type.

More specifically, the invention pertains to 5 means for agitating carbide at the feed or discharge outlet of the carbide hopper in medium pressure acetylene generators having a gas storage chamber of substantially constant volume, and a carbide hopper provided with an outlet valve 10 that is operated by a spring balanced diaphragm responsive to variations in the pressure of the acetylene gas within the generator, the connection between the diaphragm and the carbide valve being such that a decrease in gas pressure opens 15 the valve and an increase in gas pressure closes the valve.

In generators of this type there is a delay between the change in gas pressure and the change in rate of carbide feed, and this delay causes 20 undesirable fluctuations in gas pressure. Therefore, the chief object of this invention is to reduce this delay to such an extent that the fluctuations in gas pressure within the generator will not cause undesirable fluctuations in the flame of gas 25 consuming devices connected with the generator. One cause of this delay is a caking or bridging of the carbide at the outlet of the carbide hopper, and various devices have been proposed for agitating the carbide valve in generators of this type 30 to prevent this bridging and thereby secure more uniform gas pressure, but as the power for agitating the valve is usually obtained from the movement of gas drawn from the generator, the valve may be agitated while it is closed and this movement tends to cause the finer particles of carbide 35 to sift past the valve and thereby defeat the purpose of the agitator. Therefore, another object of this invention is to agitate the carbide near the carbide valve without agitating the valve or 40 the valve seat.

In prior devices of this type the movement has been intermittent, and the interruption in movement tends to cause fluctuations in gas pressure within the generator. Therefore, another object 45 of this invention is to agitate the carbide continuously while gas is being drawn from the generator.

Other objects are to provide means of the class described that is rugged in structure, reliable in 50 operation, uniform in action, economical of power, and effective in purpose. These and other aims, objects, and novel features will appear in the following specification and the accompanying illustrations, in which:

Fig. 1 is a fragmentary vertical sectional view

of the carbide feeding mechanism of an acetylene generator incorporating one example of an application of my invention;

Fig. 2 is a sectional view along a horizontal plane at 2—2 of Fig. 1 showing the structure of Fig. 1 in plan, turned through 90°; a portion of the carbide hopper is broken away to show the motor and its connections; 5

Fig. 3 is an enlarged sectional view along a vertical plane at 3—3 of Fig. 2 showing the structure of the hopper outlet; 10

Fig. 4 is a fragmentary vertical sectional view of the feeding mechanism of an acetylene generator incorporating another example of an application of my invention; 15

Fig. 5 is a sectional view along a horizontal plane at 5—5 of Fig. 4 showing the means for driving the agitator;

Fig. 6 is a sectional view along a horizontal plane at 6—6 of Fig. 4 showing the structure of 20 the agitator; and

Figs. 7, 8, 9 and 10 are fragmentary views of alternative forms of the carbide agitator shown in Fig. 6.

The agitating device as incorporated in the 25 two embodiments of applications of the invention is deemed novel regardless of the means for supplying the motive power, which may be electric, hydraulic, weight, or spring, driven, instead of the pneumatically driven motors shown in Figs. 2, 4 30 and 5.

The motor shown in Figs. 4 and 5 is covered by Patent No. 2,090,575 issued on my copending patent application having Serial No. 570,929, and the motor shown in Fig. 2 is covered by Patent No. 35 2,061,898 issued on my copending patent application having Serial No. 652,139.

Other outstanding features of my invention, which I believe to be novel, are: the means for agitating the carbide in close proximity to the feed 40 opening without agitating either the feed valve or the valve seat, or in any way modifying the movement or operation of the feed valve; the means for agitating the carbide continuously while gas is being drawn from the generator without causing pulsations or fluctuations in the pressure of the gas at the outlet of the generator; the means for moving the agitator so that it will remain in close proximity to the carbide feed valve when it is partially open as well as when it is closed; the 45 means for providing an agitator in which the wearing surfaces are protected from carbide dust and provided with a quantity of lubricant sufficient for a long period of operation; and also the means for providing an agitator that has no 50 55

appreciable tendency to open the carbide valve or cause carbide to feed when it is closed.

The invention, as embodied in the structure of an acetylene generator shown in Figs. 1, 2, and 3, comprises a rotatable sleeve within the outlet of a carbide hopper and means for rotating the sleeve while gas is being drawn from the generator.

The generator comprises an outer casing 10 adapted to contain water and acetylene, a carbide hopper 11 having an inverted conical bottom 12 provided with a central depending outlet 13, and a valve 14, for controlling the flow of the granular carbide through the outlet into the water to generate acetylene. The valve 14 is operated by a diaphragm 15 which is responsive to variations in gas pressure within the generator. The pressure of gas on the diaphragm 15 is balanced by a spring 16, and the tension of the spring 16 may be varied by manually moving an adjustable spring abutment 17 to vary the gas pressure within the generator.

The carbide valve 14 is joined to the diaphragm 15 by a bell crank 18 which may be moved by a cam 19 carried by a cross shaft 20 and operable by handle 21 attached thereto outside the generator to close the carbide valve 14 while the generator is being recharged or transported with a charge therein.

The bottom 12 of carbide hopper 11 is provided with a central opening 22, and attached to the lower side of bottom 12 around opening 22 by suitable means such as a fusion weld is a depending cylindrical drip collar 23. Secured within drip collar 23 by suitable means such as bolts or cap screws 24 is the upper portion 25 of a gear housing, hopper outlet, or valve seat, to which a lower portion 26 is held by a plurality of bolts such as 27 which extend through ears 28 on each of the portions or sections near the joint therebetween. The joint between housing 25, hopper bottom 12, and drip collar 23, is sealed by a gasket 29 of suitable material such as rubber, and at the joint between housing portions 25 and 26 suitable recesses are formed to provide a gear chamber 30.

The gear housing or hopper outlet 13 is cylindrical in contour and carbide from hopper 11 is fed downward through the central opening or outlet 31 by gravity. The members 25 and 26 forming the hopper outlet are thickened somewhat at the point of junction to provide space for the gear chamber 30, and the lower end of lower section 26 forms a seat 32 for carbide valve 14. Gear chamber 30 is annular in form and extends around outlet 31 at the junction of members 25 and 26 a short distance above valve seat 32. Within chamber 30 a ring gear 33 is held from vertical movement between annular guiding elements 34 and 35 protruding from the upper and lower wall of chamber 30 respectively.

Secured within gear 33 by suitable means such as a joint of compression, or solder, or both, is a cylindrical sleeve 36 which extends downward within member 26, forms a prolongation of outlet opening 31, and terminates at shoulder 37 in close proximity to and just above valve seat 32 but out of contact with valve 14 when the latter is in closed position. An annular projection 38 extends downward from member 25 a short distance within sleeve 36 to close the upper edge of chamber 30 and provide a support or bearing for sleeve 36 which may also be supported by the inner surface 75 of member 26.

Gear chamber 30 is enlarged somewhat at one side to provide space for a worm gear 39 that meshes with ring gear 33 and is rigidly mounted on a shaft 40 which is journalled in suitable bearings 41 and 41' formed in sections 25 and 26, and through one of which bearings it extends outward and is connected with the rotating shaft of pneumatic motor 42 by a suitable coupling 43. Motor 42 is connected with, and is also supported by the inner end of gas outlet conduit 44 within the generator. The outer end of conduit 44 is connected through a suitable flame arrester 45 to the gas outlet or service line of the generator.

Gear chamber 30 may be packed or partially filled with a suitable lubricant such as medium graphite grease as the chamber is dust proof and therefore the grease will be retained throughout a long period of operation. Member 26 is provided with an annular drip rib 46 to prevent condensed moisture from running down the outside of hopper bottom 12 and outlet 13, and reaching the carbide in the outlet opening 31 within outlet 13.

The carbide agitating device just described is operated by the movement of gas drawn from the generator. The gas within the generator enters the inlet of motor 42 through which it passes into conduit 44 and then to the outlet line where it is used.

In passing through motor 42 the gas causes motor coupling 43 to rotate and this movement is transmitted through shaft 40 to worm gear 39 which in turn rotates ring gear 33 and sleeve 36 which agitates the carbide in hopper outlet 13 close to outlet valve 14 and valve seat 32 without moving either, or in any way modifying the movement of valve 14 or altering its operation. Also the rate of agitation is proportional to the rate gas is drawn from the generator.

Valve 14 may open and close in response to the movement of diaphragm 15 in the usual way, and the continuous movement of agitating sleeve 36 in close proximity to outlet 31 and valve 14 prevents the carbide in the outlet from caking or bridging so that it is in condition to escape and feed uniformly from the outlet the instant valve 14 opens. Therefore, the delay between a change in gas pressure and a change in the rate of carbide feed is reduced to a minimum.

The application of the invention as embodied in the structure shown in Figs. 4 to 10 comprises a carbide agitator 47 within the outlet of a carbide hopper 11 and means for rotating the agitator while gas is being drawn from the generator.

The generator comprises an outer casing 10 and a carbide hopper having an inverted conical bottom 12 provided with a central opening or outlet 48. The passage or feeding of carbide through outlet 48 is controlled by a carbide valve 14 operated by a pressure responsive diaphragm 15 the same as in the foregoing example of an embodiment of the invention.

Located within hopper 11 at outlet 48 close above carbide valve 14 is an agitator 47 carried by a shaft or vertical spindle 49 journalled in bearing 50 carried by an inturned portion 51 of hopper bottom 12. Secured to shaft 49 above bearing 50 by suitable means such as a key is gear 52 which meshes with a rack 53 carried by or operated by reciprocating shaft 54 of pneumatic motor 55. Motor 55 is connected with and supported by the inner end of gas outlet conduit 44, and it may be further supported by a suitable bracket such as 56. A suitable guide such as 57 carried by an adjacent member such as bearing 75

50 may also be provided to hold the gear teeth of rack 53 in mesh with those of gear 52.

In order to locate agitator 47 close to the upper surface of carbide valve 14 and still not interfere with its movement in case lumps of carbide become caught between agitator 47 and valve 14 when it moves to closed position, agitator 47, agitator spindle 49, and gear 52, are provided with space to move upward with respect to hopper outlet 48 and bearing 50, and gear 52 is provided with a face of suitable width to allow such movement without becoming disengaged from rack 53. The lower portion of agitator 47 may be just above but close to valve 14 when in closed position, or the agitator may follow the valve a short distance as it opens.

The shape, structure, or contour of the agitator may be of any suitable form such as fingers, paddles, a spiral or helical spring, a lift screw, etc., and the direction of rotary agitating motion may be reversed periodically each time the reciprocating motor 55 reverses, or two racks 53 and gears 52 may be provided, together with a conventional ratchet or overrunning clutch drive connection between gears 52 and shaft 49, to rotate the agitator continuously in one direction. Although shaft 54 of motor 55 reciprocates or reverses its direction of axial movement periodically, the change in direction occurs almost instantaneously and therefore there is substantially no interruption in the movement of the agitator.

As already mentioned, the form of the agitator may be varied to meet different conditions of service, and adequately agitate different grades of commercial carbide. Agitator 47 shown in Figs. 4 and 6 is provided with a plurality of radial arms 58. Although an agitator having four arms is shown the number as well as the shape may be varied. Agitator 59 shown in Fig. 7 is a conical helix of wire or rod. The size, shape, spacing and direction of turns, may be varied to meet different conditions. Agitator 60 shown in Figs. 8 and 9 is a short, hollow, inverted, truncated conical member or ring, closely fitting the inside of hopper 12 close to the outlet 48, and joined to shaft 49 by a cross member 61. The connection between the agitator 60 and shaft 49 may be different from that shown. Agitator 62 shown in Fig. 10 is a spiral of suitable size terminating in a plurality of fingers 63. The number of fingers and the direction, size, and pitch of the spiral may be different from that shown.

As in the previous example of an embodiment of the invention, the motion of the agitator is derived from the movement of gas drawn from the generator. The gas within the generator enters the inlet of motor 55 through which it passes into outlet conduit 44. This movement of gas operates motor 55 which reciprocates shaft 54 and rack 53, which rotates gear or pinion 52, spindle 49, and agitator 47.

In order to provide space for the agitator operating mechanism, part of conical hopper bottom 12 is replaced by mechanism cover or casting 51, 64, and 65, which may be of any suitable shape or form other than that shown.

The motors shown in Figs. 2, 4 and 5, offer a substantially constant and uniform, although slight resistance to the flow of gas therethrough, and therefore they tend to cause no undesirable fluctuations in gas pressure in the outlet or service line of the generator.

Where the material of which the component parts are formed is not mentioned it is to be understood that conventional material has been employed. Also, that any conventional, suitable, or equivalent material whether specified or not, may be employed.

It is understood that the size, shape, form, and relative location of the various component parts may be changed or altered, as long as their function is retained, and the improved mechanisms may be incorporated in other types of gas generators or devices, without departing from the range of the invention or the scope of the claims.

I claim:—

1. In an acetylene generator; a carbide hopper having a carbide feed outlet; a valve cooperating with said outlet for controlling the rate of said feed; a sleeve within said outlet through which said carbide passes for agitating carbide therein; and means for moving said sleeve. 15

2. In an acetylene generator; a carbide hopper having a carbide feed outlet; a valve for controlling the rate of said feed; a rotatable sleeve forming the inner wall of said outlet for agitating carbide therein; and means for rotating said sleeve. 25

3. In an acetylene generator; a carbide hopper having a carbide feed outlet; a valve for controlling the rate of said feed; a sleeve within said outlet through which said carbide is fed having the lower edge thereof in close proximity to said valve; and means for rotating said sleeve to agitate carbide at said outlet. 30

4. In an acetylene generator; a carbide hopper having a carbide feed outlet; a valve for controlling the rate of said feed; a carbide agitating sleeve within said outlet through which carbide passes to reach said outlet; a ring gear surrounding said sleeve and movable therewith; a worm gear in mesh with said ring gear; and means for 40 rotating said worm gear to agitate carbide at said outlet. 35

5. In an acetylene generator; a carbide hopper having a carbide feed outlet; a valve for controlling the rate of said feed; a carbide agitator within said outlet; a gear movable with said agitator; a rack in mesh with said gear; and means for reciprocating said rack to agitate carbide at 45 said outlet. 50

6. In an acetylene generator; a carbide hopper having a carbide feed outlet; a feed control valve; a carbide agitator within said outlet; a gear movable with said agitator; a member having teeth in mesh with those of said gear; and means for moving said member to agitate carbide at 55 said outlet. 55

7. In an acetylene generator; a carbide hopper having a carbide feed outlet; a feed control valve; an annular carbide agitator within said outlet through which carbide passes; a gear movable 60 with said agitator; a member having teeth in mesh with those of said gear; and means for moving said member to agitate carbide at said outlet. 65

8. In an acetylene generator; a carbide hopper having a carbide feed outlet; a feed control valve; a carbide agitator within said outlet; gears for moving said agitator enclosed in a dust proof chamber containing a lubricant; and means for driving said gears to agitate carbide at said outlet. 70

MAURICE P. DE MOTTE.
